UNITED STATES PATENT OFFICE.

SQUIRE ROBINSON, OF SOUTHBURG, CONNECTICUT.

WRENCH.

SPECIFICATION forming part of Letters Patent No. 320,172, dated June 16, 1885.

Application filed July 22, 1884. (No model.)

To all whom it may concern:

Be it known that I, SQUIRE ROBINSON, a citizen of the United States, residing at Southbury, in the county of Hartford and State of Connecticut, have invented certain new and useful Improvements in Wrenches, of which the following is a specification.

My invention relates to that class of so-called "monkey-wrenches" in which the movable jaw is actuated by a screw secured rotatably in a frame formed as an integral part of the wrench-bar, or attached fixedly thereto, my immediate object being to simplify somewhat the construction of said wrench so that the actuating-screw and its supporting-frame may be cheaply made, quickly assembled, and when so assembled may rotate freely, with no tendency to cramp or rattle.

Figure 1 is a side elevation of my wrench, and Fig. 2 is a longitudinal section, partly in elevation, of parts thereof.

The fixed jaw A, wrench-bar B, and movable jaw C, are all old and well known. The screw D, and its knurled head E are of the same general form as the ordinary screw and head. They are either made in one piece or rigidly connected, so as to be practically integral. In the outer end of the head I drill an axial hole, a, Fig. 2, in which I place the separately-formed loose journal-pin b. I also make this hole deep enough to receive the spring c.

F designates the ferrule, G the step, and H the recessed shoulder, all formed in one piece or otherwise made practically integral. The interior of the forward part of the ferrule is squared to fit the wrench-bar, while the other part is round to inclose the end of the wooden handle I, as in prior wrenches. The face of the step G—that is, the side which confronts the shoulder H—is provided with a recess or bearing for the end of the journal-pin b, and the distance between this face and said shoulder is such that the head of the screw neatly fits therein, as shown.

In order to assemble the parts the journal-pin is pushed inward against the spring c until its outer end is flush or nearly so with the mouth of the hole in the head E. The screw-head and spring-pressed pin are then moved bodily sidewise to bring the screw-head in

proper position between the face of the step G and shoulder H, and so soon as the journal-pin b is directly in front of its bearing in the step the spring will force said pin into place 55 and hold it there, as shown in Fig. 2. By this construction the parts are readily assembled, and when assembled the integral step, ferrule, and shoulder furnish a firm and durable support for the screw, while there is less tendency 60 for the screw to cramp and bind in place under strain than there is when the journal is integral with the screw. I find in practice, too, that the spring-pressed pin b acts to prevent the rattling of parts which invariably follows 65 when said parts are carelessly fitted or become worn by use.

It is a fact well known to those who have occasion to use screw monkey-wrenches that there is a constant tendency on the part of the 70 jaw-actuating screw to rotate and unscrew slightly at every jar, and also while in the act of removing the wrench from and attaching it again to the nut or bolt which is being turned, thus allowing the movable jaw to work slowly 75 away from the fixed jaw and slip on the nut, unless said movable jaw is frequently adjusted to fit said nut. In my new device, while the spring c is not stiff enough to prevent the operator from turning screw D to adjust jaw C, said 8c spring, by constantly forcing pin b forward against its seat, acts as a friction-tension to check any tendency on the part of screw D to work loose with ordinary use. It should be noticed that the separately-formed loose 85 journal-pin b is necessarily loosely fitted at both ends—that is, within the head of the screw and within the step—and the fact that there is less tendency for the screw to cramp and bind in place under strain than in prior 90 wrenches is in a measure due to this construction.

The construction of the recessed shoulder, the step, and the ferrule which embraces the wrench-bar, all in one piece or integral, is of 95 great importance in a combination where the separately-formed journal-pin b is employed, because the screw is held closely up to the step, and in case the ferrule works back toward the handle end of the wrench-bar under 100 continued use, as is often the case, the screw will also work back with it, and there will be

no liability of the journal - pin ever working out of place.

I am aware that a prior patent to myself shows an integral ferrule - step and recessed shoulder, with a screw having an integral head and journal-pin, and I hereby disclaim the same.

I am also aware that prior patents to others show somewhat similar wrenches, in which 10 the screw having an integral head is pivoted to the step by a pin rigidly fixed in the step, while one end extends into an axial hole in the screw - head, upon which pin the screw freely rotates. Another prior patent shows a 15 wrench having a wrench - bar, a fixed and a movable jaw, the latter operated by a nut or worm, which engages a rack on the side of the bar, said nut or worm being mounted upon a hinged but non-rotatable axle, which is held in 20 position by a spring-pressed pin or latch. This latter wrench is materially different from mine, and particularly so in the fact that neither the spring nor the pin or latch ever comes in con-

tact with any rotary part, and that the pin has no contact whatever with any part which receives the end-thrust of the movable jaws, or any part that is at all analogous to a step in the sense of that term as herein employed. All of said prior art is hereby disclaimed.

I claim as my invention—

In a wrench of the class described, the ferrule E, the step G, having the pin - receiving recess or bearing, and the recessed shoulder H, all made integral and adapted to be slipped upon the wrench-bar, as described, in combination with the headed screw D E, having the axial hole in its head end, the journal-pin b, loosely fitted within the step G and also within the screw-head, and the spring for holding said journal-pin in place, all substantially as described, and for the purposes specified.

SQUIRE ROBINSON.
